Primary Examiner — April Rivas(74) *Attorney, Agent, or Firm* — Lieberman & Brandsdorfer, LLC(57) **CLAIM**

The ornamental design for a container wagon, as shown and described.

DESCRIPTION

FIG. 1 is a front perspective view of a container wagon showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines are included for the purpose of illustrating portions of the container that form no part of the claimed design.

1 Claim, 7 Drawing Sheets# US D873,086 S
